(57) **CLAIM**

The ornamental design for a joystick for endoscope operating unit, as shown and described.

DESCRIPTION

FIG. 1 is a perspective view of a joystick for endoscope operating unit, showing an embodiment of my new design; FIG. 2 is a front view thereof; FIG. 3 is a rear view thereof; FIG. 4 is a top view thereof; FIG. 5 is a bottom view thereof; FIG. 6 is a left side view thereof; FIG. 7 is a right side view thereof; and, FIG. 8 is a sectional view thereof; taken along line 8-8 in FIG. 2.

The broken lines in FIGS. 3 and 8 show portions of the joystick for endoscope operating unit that form no part of the claimed design.

1 Claim, 3 Drawing Sheets
